UNITED STATES PATENT OFFICE.

ELEUTHERE SIX, OF MILTON, PENNSYLVANIA, ASSIGNOR TO SUSQUEHANNA SILK MILLS, OF NEW YORK, N. Y., A CORPORATION OF NEW YORK.

SELF-THREADING THREAD-TENSION DEVICE FOR SHUTTLES.

Application filed October 3, 1921. Serial No 505,052.

To all whom it may concern:

Be it known that I, ELEUTHERE SIX, a subject of the King of Belgium, residing at Milton, in the county of Northumberland 5 and State of Pennsylvania, have invented certain new and useful Improvements in Self-Threading Thread-Tension Devices for Shuttles, of which the following is a specification, reference being had therein to 10 the accompanying drawings.

This invention relates to a self-threading thread tension device for shuttles, and the object of the invention is the construction of a simple and efficient tension device for 15 automatic shuttles, whereby the thread from the bobbin will fall into both the threader block and tension device as soon as the pick of the shuttle is started.

With the foregoing and other objects in 20 view, my invention comprises certain novel combinations, constructions and arrangements of parts as will be hereinafter described, illustrated in the accompanying drawing, and more particularly pointed out 25 in the appended claims.

In the drawings:

Figure 1 is a fragmentary, perspective view of a shuttle-body, showing my tension device applied thereto.

Figure 2 is a sectional view, taken on line 2-2, Fig. 3, and looking in the direction of the arrows.

Figure 3 is a sectional view, taken on line 3-3, Fig. 2, and looking in the direction of the arrows.

Figure 4 is a perspective view of the two blocks and the metal plate.

Referring to the drawings by numerals, 1 designates the shuttle-body, 2 the bobbin 40 therein, and 3 is the threader block.

In carrying out my invention, I employ two elements or "blocks" 4 and 5 placed in the compartment "A" of the shuttle-body 1 (Fig. 2); these blocks will be known as the 45 primary block 4 and the auxiliary block 5, and a substantially inverted L-shaped plate 6 is employed for the purpose hereinafter specified.

In the threader block 3 is formed a cut- 50 out portion 7, which receives the lateral extensions 8 of the blocks and plates, assisting in holding the tension device in an assembled position for efficient action in conjunction with the threader block 3.

55 The primary block 4 increases in width

from its top to its bottom so that the inner face 9 is on an incline, as shown in Fig. 2. The auxiliary block 5 decreases in width from its top to its bottom, so as to place its inner face 10 in an inclined position, so that 60 the filling thread will fall readily between the blocks, by reason of the contiguous faces of the blocks registering with the corresponding opening or slot in the threader block.

The auxiliary block 5, near its upper end, is cut-out on its inner face, producing a spring-receiving and holding pocket 11; the plate 6, preferably formed of metal, is of an inverted L-shape, corresponding in 70 general contour with the primary and auxiliary blocks 4 and 5, and interposed between plate 6 and block 5 is coil spring 12; one end of the coil spring is seated in pocket 11, and the other end of said spring bears 75 against the face of plate 6. Screw 13 is threaded through the side of the shuttle-body 1 and its inner end engages the plate 6, so that by rotating the screw, plate 6 may be pushed inwardly, increasing the tension 80 of the spring 12 for holding the blocks closer together, or by unscrewing screw 13, the plate 6 can be caused to press against the shuttle-body direct, thereby decreasing the strain upon the spring and its pressure 85 against the auxiliary block 5.

The two blocks are left free to have some bodily movement in the shuttle-body, with respect to a transverse "play;" and by means of the screw 13, plate 6 and spring 90 12, the tension or pressure upon the filling passing through the device, can be greatly and efficiently controlled or adjusted.

I use the term "blocks" in this specification and appended claims in a broad sense, 95 because these blocks could be styled "jaws," or "clamping elements," or the like, and I do not limit myself to any specific kind of material in constructing the "blocks," nor the construction of plate 6, although the 100 "blocks" are preferably made from a fibre composition, and the plate is preferably formed of metal.

While I have described the preferred embodiment of my invention, and have illustrated the same in the accompanying drawings, certain minor changes or alterations may appear to one skilled in the art to which this invention relates, during the extensive manufacture of the same and I, 110

therefore, reserve the right to make such alterations or changes as shall fairly fall within the scope of the appended claims.

What I claim is:

- 5 1. In a device of the class described, the combination with a shuttle-body, a threader block provided with a cut-out portion in said shuttle-body, of a primary and an auxiliary block in said shuttle-body, each block
10 provided with a lateral extension at one end extending into and fitting snugly within said cut-out portion of the threader block, one of said blocks provided with a spring-receiving pocket, a plate provided with an
15 extension projecting into said cut-out portion of the threader block, a spring in said spring-receiving pocket and bearing against said plate, and a screw in said shuttle-body and normally engaging said plate, as and
20 for the purpose set forth.
2. In a device of the class described, the combination with a shuttle-body, of a tension device in said shuttle-body comprising a primary block increasing in thickness
25 from its upper end to its lower end, an auxiliary block decreasing in thickness from its upper end to its lower end, whereby the space between the blocks will be at an angle to the perpendicular, a plate contiguous to
30 said auxiliary block, a spring between said auxiliary block and plate, and a screw in said shuttle-body and engaging said plate, as and for the purpose set forth.
3. In a device of the class described, the
35 combination with a shuttle-body, of a pri-

mary block narrow at its top and wide at its bottom in said shuttle-body, an auxiliary block wide at its top and narrow at its bottom in said shuttle-body, whereby the space between said blocks will be at an angle to the perpendicular, and manually adjustable means in the shuttle-body and engaging one of the blocks for controlling the relative position of the blocks with respect to each other within the shuttle-body, as and for the 45 purpose set forth.

4. In a device of the class described, the combination with a shuttle-body, of a pair of blocks in said shuttle-body, a screw in said shuttle-body, a plate in the shuttle-body 50 against the inner end of said screw, and a spring bearing against the plate in alignment with the screw and also bearing against one of the blocks.

5. In a device of the class described, the combination with a shuttle-body, a threader block provided with a cut-out portion in said shuttle-body, of a primary and an auxiliary block in said shuttle-body, each block provided with a lateral extension at one end extending into and fitting snugly within said cut-out portion of the threader block, whereby the blocks will be firmly held to move freely and be prevented from binding, and means for yieldably urging the blocks together, as and for the purposes set forth.

In testimony whereof I hereunto affix my signature.

ELEUTHERE SIX.
